Attorney

UNITED STATES PATENT OFFICE.

JOHN F. ROGERS, OF CLEVELAND HEIGHTS, OHIO, ASSIGNOR TO THE WELLMAN-SEAVER-MORGAN COMPANY, OF CLEVELAND, OHIO, A CORPORATION OF OHIO.

FUEL-FEEDING MECHANISM.

Application filed August 21, 1920. Serial No. 405,163.

To all whom it may concern:

Be it known that I, JOHN F. ROGERS, a citizen of the United States, residing at Cleveland Heights, in the county of Cuyahoga and State of Ohio, have invented a certain new and useful Improvement in Fuel-Feeding Mechanism, of which the following is a full, clear, and exact description.

This invention is in the nature of an improvement upon the fuel feeding mechanism for solid fuel which forms the subject matter of the Rogers and McClimon Patent No. 1,330,749.

The principal object of the invention is to effect a substantial reduction in the cost of producing such feeding mechanism.

The invention consists in the construction and combination of parts shown in the drawing and hereinafter described and definitely pointed out in the appended claims.

In the drawing, Fig. 1 is a side elevation of so much of the fuel feeding mechanism as is necessary to disclose the present invention; Fig. 2 is a front view partly in section, and Fig. 3 is a side elevation of a machined ring from which segments are cut to form the valve holding plates 40.

The feeding mechanism is like that which is shown in said prior patent in that it includes a chute 10 which is intended to be secured on the top of a gas producer and through which the fuel is fed. The lower or base portion 10^b of the chute is formed with a semi-cylindrical top surface 12 through which is a downwardly extended fuel passage 13 which will of course be in open communication with a hole through the top of the gas producer. This semi-cylindrical top surface 12 of the chute base 40 serves as a valve seat on which a rotatable cylindrical fuel valve 30 is fitted.

This valve includes a central hub 35, end plates 36 and a plurality of radial partitions 34 which extend from one end plate to the other, thereby forming in the valve a plurality of peripherally opening pockets 31.

In the respects specified the construction shown is like that which is shown and described in detail in said prior patent.

In the present construction, however, at each end of the valve, the end plate is provided with an integral coaxial outwardly extended cylindrical boss 39 of smaller diameter than the end plate.

40—40 represent two plates which are in the form of segments of a ring. These are secured to the side walls of the chute above the valve. They extend downward, and their inner faces 41 overlap and engage the outer surfaces of the end plates of the valve, and thereby prevent endwise movement of the valve. The lower faces of these plates 40 are arc-shaped and fit the cylindrical surfaces of the bosses 39 and thereby serve to prevent the valve from lifting from its seat as it is rotated.

The described construction may not be any more efficient than other means for preventing the valve from moving endwise and from rising from its seat; but it is substantially cheaper than any other equally efficient construction with which I am familiar. The valve may be a casting, and it may be rendered suitable for use by a simple turning operation which finishes up the cylindrical surfaces of the valve arms and of the end bosses, and so much of the single trunnion as is necessary. In the preparation of the plates 40 a cast ring, as shown in Fig. 3, may be employed, by machining one side and the inner periphery of the ring. When this has been done the ring may be sawed into segments, and each will be of the required size and shape to serve as the described plates 40, when bolted to the sides of the chute above the valve.

One of the end plates 36 may be provided with an integral outwardly extended trunnion 38 to which may be applied the power for turning the valve. The mechanism by means of which the valve is turned may be substantially like that shown in said prior patent.

Having described my invention, I claim:

1. In feed mechanism for gas producers, the combination of a chute containing a concave valve seat forming not more than half of a cylinder and through which is a fuel discharge passage, a cylindrical valve which is rotatably supported upon said seat and has ends and one or more peripherally opening fuel pockets between said ends,—each end plate being formed with an outwardly projecting coaxial cylindrical boss of smaller diameter, and plates fixed to the sides of the chute above the valve,—each plate overlapping the outer surface of the adjacent end, and having an arc-shaped lower surface

which overlies the cylindrical boss on the valve and prevents the valve from lifting from its seat.

2. In feed mechanism for gas producers, 5 the combination of a chute containing a concave valve seat forming not more than half of a cylinder and through which is a fuel discharge passage, a cylindrical valve which is rotatably supported upon said seat and 10 has ends and one or more peripherally opening fuel pockets between said ends,—each

end being formed with an outwardly projecting coaxial cylindrical boss of smaller diameter, and segment shaped plates secured to the sides of the chute above the valve and 15 extended down to overlapping relation to the ends of the valve, said plates having finished arc-shaped lower edges which fit over the peripheries of said bosses.

In testimony whereof, I hereunto affix my 20 signature.

JOHN F. ROGERS.
